DESIGN FOR A KNITTED FABRIC

Jack Minoff, Newark, N. J.

Application September 29, 1937, Serial No. 71,856

Term of patent 14 years

To all whom it may concern:

Be it known that I, Jack Minoff, a citizen of the United States and a resident of Newark, county of Essex, and State of New Jersey, have invented a new, original, and ornamental Design for a Knitted Fabric, of which the following is a specification, reference being had to the accompanying drawing, forming part thereof.

The figure is a plan view of the knitted fabric, showing my new design.

I claim:

The ornamental design for a knitted fabric substantially as shown.

JACK MINOFF.
